I. DION

SQUARE

Filed March 18. 1922

Inventor

Attorney:

UNITED STATES PATENT OFFICE.

ISAIE DION, OF SWANSEA, MASSACHUSETTS.

SQUARE.

Application filed March 18, 1922. Serial No. 544,854.

To all whom it may concern:

Be it known that ISAIE DION, a citizen of the United States, residing at Swansea, in the county of Bristol and State of Massachusetts, has invented certain new and useful Improvements in Squares, of which the following is a specification.

This invention relates to squares and consists in novel features hereinafter shown, 10 described and claimed.

In the drawings forming a part of this specification, like characters of reference designate corresponding parts in the seven figures, in which—

15 Figure 1 is a plan view of a square embodying the features of the invention with the parts in their normal closed position,

Figure 2 is an enlarged top plan view of the hinge of the square with the blade and 20 tongue in full open position,

Figure 3 is a similar plan view of the back thereof,

Figure 4 is a similar top plan view with the blade and tongue in a partially open 25 position.

Figure 5 is an enlarged cross sectional view through the blade and tongue taken on line 5—5 of Figure 1,

Figure 6 is a detail sectional view taken 30 on line 6—6 of Figure 4, and

Figure 7 is a detail sectional view taken on line 7—7 of Figure 2.

Referring to the drawings, the square 35 comprises a blade 10 and tongue 11 which are pivotally connected by means of a member 12.

The blade and tongue members are longitudinally recessed, as best shown in Figure 5, so that they will fold together into a 40 compact a form as possible. The tongue 11 is provided with a projecting portion 13 at one end on its upper surface over the recessed portion. This portion 13 is formed round concentric with the axis of the pivot

45 and flares conically inward toward the top. Blade 10 is further recessed at 14 so as to receive the bevelled projection 13, and its lower portion is cut away at 15, and the blade and tongue are so shaped at their

50 ends that they will complementally receive each other so that they can be pivoted together and open and close on each other. The pivot 12 comprises a bevelled mem-

ber 16 extending into a bevelled aperture in the upper surface of the tongue and a 55 bevelled, or so called "flat-headed" screw 17 extends up through a bevelled aperture in the bottom of the blade 10 for holding the member 16 in place. The screw is threaded into the member 16 eccentrically so that the 60 two members securely engage each other and the blade member. The pivot member 16 and the screw particularly are thus prevented from turning in relation to the blade member so that the blade may be considered 65 as carrying the pivot.

The blade and tongue may be locked in open position by means of one or more screws such as 18 and 19 which are carried in apertures in the top and bottom faces 70 of blade and tongue respectively. Screw 18 set in the upper face of the blade is adapted to have its outer edge engage a recess 20 in the projection 13 of the tongue. The screw has its edge cut away at 21 and is 75 notched at 21', and when it is turned so that the cut portion is presented toward the projection and the notch so as to receive the lower edge thereof, the tongue can be turned on the pivot. Screw 19 is similarly cut 80 away at 22 and positioned in the tongue so as to cooperate with a recess 23 in the blade.

When the blade and tongue are closed, another screw 24, similar to screws 18 and 19, can be used to lock the members together. 85 This screw is cut away at 25 and the tongue recessed at 26 to receive the edge of the screw. The screw can be turned down tight upon the tongue and blade for locking them, or rotated in a reverse direction until the 90 cut away portion 25 faces the recess 26 thus releasing the members.

In order to lock the blade and tongue at various angles with each other so that the instrument may be used as a bevel, the blade 95 may be provided with a screw 27 positioned therein substantially radially of the axis of the pivot 12, in order that its point may engage in notches 28 in projection 13. The screw is preferably provided with a knurled nut 29 positioned in an aperture in the blade, and upon turning it with the fingers, the screw is projected toward or retracted 100 from the projection 13.

In case it is found necessary to adjust or 105 true the square, the tongue is provided with

a screw 30 which can be extended from the end of the tongue as an abutment for engaging the blade.

The square can be calibrated in the usual manner and one of the faces, the top face as disclosed in Figure 1, can be calibrated in degrees around the pivot so that the instrument can be used as a protractor. The back face can also be calibrated for other purposes, such as a scale giving rafter cuts, and notches 28 can be so spaced as to correspond with various calibration marks, or they may be so small and close together that a very fine adjustment can be secured.

15 The square has been shown with two forms of locking members, screws 18 and 19 for fastening it in open position and a screw 27 for securing the members at angles of less than 90 degrees. While this is the preferable arrangement,—using the two forms in this manner—since as a square, the screws 18 and 19 will hold it most rigidly and screw 27 can be used advantageously for various adjustments, it is also possible to 20 hold the members in any of their positions, open or closed, by any one of these screws. The square is constructed so that its blade and tongue members have their faces in the same planes, and due to the complementary recesses in them they may partially close 25 upon each other. In order to further cut down the weight these members may be tapered from a thick portion at their pivot to thinner ends remote from the pivot.

30 Having disclosed one form of the invention for purposes of illustration, it is to be understood that various changes may be made in form arrangement and organization of parts as may fairly fall within the scope 35 of the invention as claimed.

What is claimed as the invention and is desired to be secured by Letters Patent is:—

40 1. A square comprising blade and tongue members pivoted to each other at their meeting ends and each being complementally recessed whereby they may be folded together, and a screw carried by the blade adapted to engage the end of the tongue remote from the pivot when the members 45 are closed upon each other for securing them together.

45 2. A square comprising blade and tongue members pivoted to each other at their meeting ends and each being complementally recessed whereby they may be folded together, said tongue having a recess in its outer end, a screw carried by the blade at a point beyond the end of the tongue remote from the pivot when the members are 50 closed upon each other, said screw being

adapted to engage the end of the tongue within said recess in the outer end of the tongue for securing the members in closed relation.

55 3. A pivot for two overlapping members comprising a pivot member having a bevelled journal portion in a correspondingly bevelled recess in one of said members and extending through said member and engaging the other member, and a screw member extending through the second member and threaded into an aperture in said pivot member eccentric to the axis of the pivot.

60 4. Two overlapping pivotally connected members, there being an aperture in one of said members concentric with the axis of the pivot and an aperture through the second member eccentric to the axis of the pivot, a pivot member passing through the concentric aperture in the first member and engaging the second member, and a screw member passing through the eccentric aperture and into the pivot member thereby securing the pivot and members in position.

65 5. A square comprising a blade and tongue members, one of said members being provided with a bevelled round projection at its end with its center between the side edges of the member adapted to fit into a correspondingly shaped recess in the other member of the square, and a pivot member concentric with the rounded projection for 70 securing the members together.

75 6. In a square in accordance with claim 5, said first named member having a series of notches in its bevelled rounded projection, a screw carried by the second, or recessed member and arranged radially of the pivot axis, and means for projecting said screw into engagement with and retracting it from 80 the notches in said projection of the first member.

85 7. A square comprising blade and tongue members complementally recessed whereby they may be folded together, a pivot between the side edges of the tongue and blade members adjacent to their ends, for securing said members together, one of said members having a rounded beveled under-cut recess concentric with the axis of the pivot, the adjacent pivoted end of the other member having a rounded portion concentric with the axis of the pivot and having a beveled projection thereon adapted to complementally engage within the under-cut portion of the first said member.

90 In testimony whereof he affixes his signature.

ISAIE DION.
